Chamberlain & Newman

UNITED STATES PATENT OFFICE.

HAROLD B. HAWES, OF BRIDGEPORT, CONNECTICUT.

SKYLIGHT.

Application filed June 19, 1923. Serial No. 646,308.

To all whom it may concern:

Be it known that HAROLD B. HAWES, a citizen of the United States, and resident of Bridgeport, in the county of Fairfield and State of Connecticut, has invented certain new and useful Improvements in Skylights, of which the following is a specification.

This invention relates to improvements in sky-light structures and particularly to supporting means for the glass panels thereof.

An object of the invention is to provide a support in which the glass will be effectually cushioned and free from metal contact, and in which expansion and contraction due to temperature change will be compensated for in a manner to maintain a weather-tight closure at all times without danger or distortion or breakage, notwithstanding the different co-efficients of expansion of the materials going into the structure. To this end it is proposed to provide improved resilient connection means between the channel rafters and the cap for retaining the glass panels.

A further object is to provide a structure including a felt contact for the glass panels and in which the felt will be maintained against the shifting and rapid deterioration.

Another object is to provide a structure which may be assembled with great facility and in which all the parts may be manufactured to size in the factory, and thereupon assembled at the building.

With the above and other objects in view, an embodiment of the invention is shown in the accompanying drawings, and this embodiment will be hereinafter more fully described with reference thereto and the invention will be finally pointed out in the claims.

In the drawings:

Fig. 1 is a perspective vertical sectional view of a sky-light construction according to the present invention;

Fig. 2 is a vertical longitudinal sectional view thereof;

Fig. 3 is a vertical sectional view of the channel rafter and supporting stirrup connected thereto;

Fig. 4 is a plan view of the same;

Fig. 5 is a perspective view showing the yieldable post and slip washer detached; and

Fig. 6 is a perspective view of the felt

strip adapted to be disposed at the under side of the glass panels.

Similar reference characters indicate corresponding parts throughout the several figures of the drawings.

Referring to the drawings, the channel rafter 10 is provided at suitable spaced points with inverted U-shaped strips 11, secured thereto by having bosses 12 pressed outwardly from their sides and engaging apertures 13 in the sides of the rafter. This structure is of great strength, may be assembled with facility by bending the sides of the channel into relation with the stirrup, so that its bosses engage the apertures and it is free of any parts which may become loose in use.

In the upper end of the stirrup there is provided a non-circular hole 14, preferably flat at two sides, and which is slidably engaged with the reduced non-circular shank 15 of a cylindrical post 16 resting at its lower shouldered end upon the upper side of the stirrup, and provided at its upper shouldered end with a reduced threaded extension 17. The cross section of the shank 15 preferably conforms to the hole 14 so that the post will not turn therein.

At the lower end the shank is provided with a slot 18 engaged by a slip washer 19, and between the washer and the under side of the stirrup a spring 20 is provided on the shank, and permits upward yielding of the post.

A felted packing strip upon which the adjacent marginal edges of the glass panels rest, is supported upon the stirrups and comprises a metal strip 21, having its longitudinal edge portions bent into channel form, as at 22, and securing the longitudinal edges of a felt strip 23 provided at the upper side of the metal strip, the felting strip being provided with apertures 24 at suitably spaced points for engagement with the posts 16. The channel portions 22, it will be noted, are disposed inwardly and spaced from the upper edges of the channel rafter, so that water of condensation forming upon the under side of the panels will flow over the portions 22 and into the trough of said channel rafter.

The glass panels 25, which span the several rafters of the skylight structure, rest at their marginal portions on the felt strip 23, and are retained in place thereon by a

cap strip 26 having longitudinal downwardly and outwardly bent edge portions 27 and a central longitudinal crown portion 28, and provided at suitably spaced points 5 with apertures 29 which engage over the threaded extensions 17 of the posts 16 so that said crown portion rests upon the upper shouldered ends of the posts. An inwardly threaded head 30 is screwed upon 10 the extension 17 and secures the cap strip in place.

A felt strip 31 is compressed beneath and housed within the cap strip to tightly engage upon the upper surface of the glass panels, being provided at suitable points 15 with apertures 32 for engagement over the posts 16.

The posts 16 are so proportioned that when the cap strip is in place, and the head 20 30 tightly screwed down, the posts are slightly raised against the tension of their springs 20, and thereby a constantly tight, but yieldable, relation is maintained between the glass panels and the supporting 25 structure; so that change in temperature, and its different expansion and contraction effects upon the materials of the structure will be compensated for in such manner that a tight closure is at all times established, 30 without danger of distortion or breakage. The flared edge flanges 27 permit the cap strip to yield under the pressure of the posts, and at the same time maintain tight closure with the glass panels.

35 I have illustrated a preferred and satisfactory embodiment of the invention, but it will be obvious that changes may be made therein, within the spirit and scope thereof, as defined in the appended claims.

40 Having thus described my invention, what I claim and desire to secure by Letters Patent is:

1. In a skylight structure, a rafter, a support thereon having an aperture, a post having a shouldered upper portion engaging the upper side of said support and a shank portion extending through and slidably in said aperture, a spring on said shank portion retaining said post and permitting upward yielding movement thereof, a cushioning strip resting directly upon said support, glass panels resting on said cushioning strip at each side of said post, a retaining strip engaging said glass panels at their upper side and having a perforation engaging said post, and means engaging said post for securing said retaining strip.

60 2. In a skylight structure, a rafter, a support thereon, a post resting upon said support and slidably mounted therein to have upward yielding movement and provided at its upper side with a reduced threaded extension forming a shoulder, a

cushioning strip directly on said support, glass panels on said cushioning strip at each 65 side of said post, a retaining strip engaging said glass panels at their upper side and having a perforation engaging said post, the strip resting on the shoulder of the post, and a threaded head engaging the threaded 70 extension of said post and adapted to secure said retaining strip thereon.

3. The combination as specified in claim 2, wherein the support has a non-circular aperture and the post is of a configuration to have 75 sliding movement only in said aperture.

4. In a skylight structure, a rafter, a support thereon and having an aperture, a post having a shouldered upper portion engaging the upper side of said support and a shank 80 portion extending through and slidable in said aperture, said shank portion being removable through said aperture and provided at its lower end with a slotted post, a removable slip washer engaging said slotted post, a spring on said shank portion disposed between the under side of said support and said slip washer and permitting upward yielding movement of the post, a cushioning strip resting directly on said 85 support, the post passing through the cushioning strip, glass panels resting on said cushioning strip at each side of said post, a retaining strip engaging said glass panels at their upper side and having a perforation 90 receiving the post, and means engaging said post for securing said retaining strip.

5. In a skylight structure, a channel rafter, an inverted U-shaped support received therein and having an aperture in its upper portion, a post having a shouldered upper portion engaging the upper side of said support and a shank portion extending through and slidable in said aperture, a spring on said shank portion retaining said post and permitting upward yielding movement thereof, a cushioning strip resting directly upon said support, glass panels resting on said cushion strip at each side of said post, a retaining strip engaging said 100 glass panels at their upper side and having a perforation engaging said post, and means engaging said post for securing said retaining strip, whereby said cushioning strip, glass panels and retaining strip are supported directly from said support, and all of the elements last mentioned can as a whole have upward yielding movement away from 105 said support.

110 Signed at Bridgeport, in the county of Fairfield and State of Connecticut, this 13th day of June, A. D., 1923.

115 HAROLD B. HAWES.
